UNITED STATES PATENT OFFICE.

ALFRED GAULARD, OF PARIS, FRANCE, ASSIGNOR TO ATELIERS DES VOSGES, OF PARIS, FRANCE, A CORPORATION OF FRANCE.

SHUTTLE LOCKING AND RELEASING CONTROL.

Application filed February 1, 1927, Serial No. 165,060, and in France February 25, 1926.

The invention relates to devices for locking and releasing the shuttle in looms and has for its object an improved control for these devices which presents, in comparison with the motions employed heretofore, the advantage of permitting an absolutely accurate adjustment of the locking and releasing points of the shuttle to be obtained.

This improved control, which is constructed with a view to permitting the locking and releasing points to be advanced or retarded and an accurate adjustment to be obtained, is characterized by the feature that the shuttle releasing lever is actuated from the rod of the batten through the medium of a combination of transmission members the position of one of which is adjustable relatively to another, for example a bent lever pivotally mounted upon the said rod, one of the arms of which lever actuates the shuttle releasing lever, the other arm being pivotally mounted on the end of a rod the other end of which is adjustably mounted in a cap pivotally mounted upon a trunnion integral or virtually integral with the frame of the loom.

A form of such an improved control is described hereinafter and illustrated diagrammatically by way of example in the accompanying drawing.

In this drawing, 1 is a leg of the batten, 2 the rod actuating the batten, 3 the shuttle locking tongue comprising at its end a rod 4. The shuttle releasing lever is formed as a bell crank lever 5—6 pivotally mounted at 7 upon the pivot of the rod 2. The function of the arm 5 is to pull back the rod 4 of the tongue 3 in order to release the shuttle. The second arm 6 of the said lever is formed with a slot 8 in which is adapted to slide freely a trunnion 9 carried by the arm 10 of a bell crank lever which is pivoted at 11 upon the rod 2. The other arm 12 of said bell crank lever is pivotally mounted at 13 upon the end of a rod 14 mounted at its other end in an adjustable manner, by means of a nut 15 and counter nut 16 for example, in a cap 17 pivoted on the trunnion 18 integral or virtually integral with the frame of the loom. 19 is the shuttle locking spring.

It will be understood that the reciprocating motion of the rod 2 and consequently of the point of pivotal mounting 11 of the bent lever 10—12 causes the locking and releasing of the shuttle by actuating the lever

6—5. It will also be understood that it is possible to adjust with as much precision as desired the lock and release points by adjusting the length of the rod 14.

Naturally, it is possible, without going outside the scope of the invention, to make modifications and improvements in details, and equivalent means may be employed.

What I claim is:

1. An improved shuttle lock and release control for looms, with adjustment of the lock and release points comprising a batten, a batten rod, a shuttle releasing lever and a combination of transmission members adapted to actuate said shuttle releasing lever by said batten rod, the arrangement being such that the position of one of said transmission members is adjustable relatively to the other, the transmission members comprising a two-armed bent lever pivotally mounted on said batten rod and a second rod adjustably and pivotally mounted at one end on the loom frame and pivotally connected at the other end to one end of said bent lever the other end of said bent lever being adapted to actuate said shuttle releasing lever.

2. An improved shuttle lock and release control for looms, with adjustment of the lock and release points comprising a batten, a batten rod, a shuttle releasing lever and a combination of transmission members adapted to actuate said shuttle releasing lever by said batten rod, the arrangement being such that the position of one of said transmission members is adjustable relatively to the other, the transmission members comprising a two-armed bent lever pivotally mounted on said batten rod, a trunnion on the loom frame, a cap pivotally mounted on said trunnion and a second rod adjustably mounted in said cap, one arm of said bent lever being adapted to actuate said shuttle releasing lever and the other arm of said bent lever being pivotally mounted on the end of said second rod.

3. An improved shuttle lock and release control comprising a shuttle locking tongue and a rod on the end of said tongue, a shuttle releasing lever comprising a bell crank lever pivotally mounted on the batten rod, one arm of said lever being adapted to act upon said tongue rod and the other arm having in it a slot, a two-armed bent lever pivotally mounted on said batten rod, a

trunnion on one arm of said bent lever, said trunnion moving in the slot on said bell crank lever and thereby providing a pivotal mounting for said arm, a second trunnion on the loom frame, a cap pivotally mounted on said trunnion, a second rod adjustably mounted at one end in said cap and at the other end pivotally connected to the other arm of said bent lever, the arrangement be-

ing such that the movement of the batten 10 rod produces the locking and releasing of the shuttle through the bell crank lever and that the moments of locking and release can be varied by adjusting the length of said second rod. 15

In witness whereof, I hereunto subscribe my signature.

ALFRED GAULARD.
